LIFTING SLING GUIDE FOR ELONGATED ARTICLES

Talford S. De Cuir, Whiting, Ind., assignor to The Lummus Company, New York, N. Y., a corporation of Delaware

Application July 17, 1945, Serial No. 605,560

5 Claims. (Cl. 294—74)

1

This invention relates to the art of lifting and erecting large objects and equipment and, in particular, to the provision of new and improved lifting lug constructions for such objects and equipment which adapt them for convenient lifting, tipping, manipulation, transportation and erection by conventional cranes, derricks and the like.

It is a particular object of this invention to provide new and improved lifting lug constructions which, though strong and positive in operation, are of such cheap and simple construction as to be readily formed or fabricated, and attached during fabrication, directly to the equipment or objects to be provided therewith; which may remain a permanent part of the object or equipment; or which may be readily and conveniently removed from the aforesaid object or equipment after erection thereof, if desired.

It is a further object of this invention to provide such lifting lug constructions which are fixed to the aforesaid objects or equipment and which cooperate with loops or bights of the lifting line or cable to form a slip-proof sling providing the ultimate positive control of the object or equipment during the lifting or erecting operation, and obviating the necessity for complicated and expensive, less positive and less slip-proof equipment such as articulated slings or other complicated appliances attached to or associated with the lifting cables and heretofore necessary for achievement of any reasonable degree of control.

It is a further object of this invention to provide a new and improved method of preparing large equipment and objects for handling by a conventional crane or derrick.

These and other objects and advantages of the invention will hereinafter appear from the following description taken with the drawing and the appended claims.

In the drawing:

Fig. 1 is a diagrammatic view, in elevation, illustrating an early position assumed by a tower equipped with lifting lugs, according to this invention, in a lifting and positioning operation;

Fig. 2 is a view similar to Fig. 1 of a subsequent position assumed during such an operation;

Fig. 3 is a similar view showing a third position, subsequent to the position of Fig. 2, assumed in the aforesaid operation;

Fig. 4 is a similar view of a fourth position assumed during that operation;

Fig. 5 is a view similar to Figs. 1 to 4 inclusive,

2

but showing the position assumed by the parts immediately prior to release of tension on the lifting line, cable, or sling, whereby the tower of Figs. 1 to 5 is set or positioned upon a predetermined base or foundation;

Fig. 6 is an end view of the tower of Figs. 1 to 5, showing a preferred manner of rigging a sling for cooperation with the lifting lugs of this invention;

10 Fig. 7 is a side view of the structure shown in Fig. 6;

Fig. 8 is an enlarged fragmentary detail view, in elevation, of one of the lifting lugs shown diagrammatically in Figs. 1 to 7; and

15 Fig. 9 is a section taken substantially on the line 9—9 of Fig. 8.

Broadly speaking, the lifting lugs of this invention may be considered as ears or projections especially provided on large or cumbersome articles or equipment such as the illustrated tower,

20 in pairs, for cooperation with slings comprising one or more bights in, or associated with, the lifting line of a derrick, crane or the like. The location of the lug is determined by the height 25 of the vessel, the distance of the lifting derrick, or the like, from the foundation on which the vessel is to be set, and the clearance height of the derrick boom above that foundation, with due respect to the center of mass or center of gravity

30 of the equipment, article, or tower, to be equipped with the aforesaid lugs and lifted thereby. Since the lugs are of cheap construction, readily attachable permanently to the tower, they may be left in place after the lifting operation

35 or, if desired, they may be cut off the tower or equipment to which they are welded when attached.

These lugs are not to be confused with equipment separate from such a tower or the like, which 40 equipment is intended to be used and re-used, over and over again.

As shown in Figs. 6, 8 and 9, the lifting lugs generally designated 10, which are similar and obverse, each comprise a pair of substantially 45 parallel channel members 12 connected by a strap or bar 14 adjacent their intermediate portion and having their lower ends joined by a rocker member 15 with the central portion 16 thereof substantially straight or planar and with

50 arcuate end portions 17 and 18 extending outwardly and upwardly of the intermediate portion 16. One arcuate end portion 17 is preferably of relatively smaller radius than the other arcuate end portion 18, whereby the rocker member 55 15, in elevation, appears somewhat similar to

the runner of a sleigh or skate turned up at both ends. For the sake of convenience, the parts are described in their final position, when the tower 11 is set in its final position wherein it is upright as are the members 12, as shown in Figures 8 and 9.

As will be understood, the members 12, 14 and 15 are welded in place, to one another, and to one side or sidewall of a piece of equipment such as the tower 11, which is desired to be lifted or placed in suitable position as, for instance, on a base or foundation 11a (Fig. 5).

Suitable angles or braces 19 and 20 may be welded to the aforesaid tower wall and to suitable parts of the lug 10 for the sake of rigidity. At its outer edge, each rocker member 15 is provided with a downwardly projecting retainer or flange 21 which preferably extends from end to end thereof, and which cooperates with an angularly disposed thrust plate 22 (Figs. 8 and 9) to guide the loops or bights 24 of the line 23 forming the sling portion or sling.

While the sling is shown in Figs. 1 to 5 in its simplest form and as comprising a single loop or bight 24 provided with loops at its opposite ends through which the eye 25 passes in conventional manner, the preferred form of sling is shown in Figs. 6 and 7. As shown in Figs. 6 and 7, the eye 25 passes through the end loops of a cable generally designated 23. The eye 25 is, of course, provided with the conventional lifting bolt 26. Suspended from the mid-portion of the eye 25 is a sheave 27 over which the mid-portion of the cable 23 extends, as shown in Fig. 6, whereby the cable 23 is divided into two loops or bights. The inner bight 24 passes over the sheave 27 and around the tower 11, one leg of this bight being disposed above the cable portion, forming the adjacent leg of the outer bight and the other leg portion of the inner bight passing beneath the adjacent leg or leg portion of the outer bight, as therein shown. By this arrangement, the tension is equalized in the cable 23 throughout the sling and the respective bights 24 of the sling cooperate to exert a wedging effect, in cooperation with the thrust plate 22, as shown in Fig. 9, whereby the upper loop or bight of the sling is wedged in the crotch formed in the retainer or flange 21, the adjacent lower surface of the rocker member 15 and the thrust plate 22, as shown in Fig. 9.

In a lifting and positioning operation, the lower end of the object (as, for instance, the tower 11) is raised and placed upon a conventional dolly or platform 30 supported on conventional rollers 31. This dolly supports the lower end of the tower and makes it possible to pass the cable 23 of the sling about the tower 11 adjacent and beneath the rocker member 15 of the lug 10. After this is done, the eye 25 is passed through the end loops of the sling formed by the cable 23 and the lifting bolt 26 is inserted through the apertures in the eye 25 and also a loop, eye, or other means (not shown) at the lower end of the lifting line or cable which is attached to the lifting apparatus comprising a derrick, crane, or the like. It is to be noted that an area between the lugs 10 and disposed in the direction toward the eye 25 is provided with lubrication 32 to prevent abrasion of the tower surface by the converging legs of the sling bight or bights. Lifting force is then applied through the lifting bolt 26 to place the parts in the position shown in Fig. 1.

From the position of Fig. 1, further applica-

tion of lifting force to the lifting bolt 26 causes the parts to move to the position shown in Fig. 2 which is accompanied by movement of the dolly 30 (guiding and partly supporting the lower end of the tower 11 and preventing it from dragging upon the earth) toward the right. As the lifting progresses, the parts move further to the position shown in Fig. 3 and thence to the position in Fig. 4, whereupon the tower 11 is supported completely by the lifting line or cable of the derrick or other lifting device, which applies lifting force to the tower 11 through the lifting bolt 26 of the eye 25. The tower is then free of terrestrial support, except through the derrick or crane, and it is swung freely through the air to final position as, for instance, directly over the support or foundation 11a, whereupon it is released and allowed to move downwardly upon the desired support.

Since the lugs 10, as described above, comprise a plurality of cheap and simple metal shapes which may be economically welded together and directly to the wall of the equipment; for instance, the tower desired to be lifted in position, the cost of these lugs is amortized many times in the avoidance or obviation of risks incident to such lifting operations where such lugs are not used, as well as in the added convenience and added control afforded in the lifting operation by these lugs. For this reason, the lugs may remain in position after the lifting operation has occurred, except where their presence is found undesirable, in which case they may be readily cut off by any suitable means as, for instance, an oxy-acetylene torch.

By the use of such lugs, equipment (such as the illustrated tower) of great size and weight may be conveniently and safely handled without damage, since they are always under complete control during the lifting and positioning operation, and since the occurrence of abrasion by the cable 23 forming the sling is totally obviated by the use of the lubrication 32.

It will thus be seen that I have provided a new and improved method of handling such cumbersome, large, and heavy equipment as above described with complete safety, security, and control, throughout the lifting and positioning operation, by means of my new and improved lugs which are of such cheap construction that they may be left in place after the lifting operation without reuse until, perhaps, when it is desired to remove the equipment, or tower, at some later date.

It is, of course, to be understood that the above description is merely illustrative and in nowise limiting, and that I desire to comprehend within my invention such modifications as are included within the scope of the appended claims.

Having thus fully described my invention, what I claim as new, and desire to secure by Letters Patent is:

1. In combination with a cumbersome object to be lifted and erected by a derrick or the like with a lifting sling, sling guiding means comprising a pair of lugs projecting outwardly from said object at opposite sides, said lugs being secured rigidly to said object, said lugs each including a member with a substantially flat central portion adapted to be disposed substantially horizontal in the final position of said object, and upwardly directed arcuate portions extending from opposite ends of said substantially flat portion and integral therewith, and a retaining flange 75 depending from the lower surface of said member

adjacent the outer edge thereof, said retaining flanges being adapted to engage a portion of a sling passing around said object below said lugs to retain said sling in position during erection of said object.

2. In combination with a cumbersome object to be lifted and positioned by a derrick or the like with a lifting sling, sling guiding means comprising a pair of obverse aligned lugs projecting outwardly from said object at opposite sides, said lugs being permanently secured rigidly to said object, said lugs each including a rocker member comprising a substantially flat portion adapted to be disposed substantially horizontal in the final position of said object and upwardly directed arcuate portions extending from opposite ends of said substantially flat portion, a retaining flange depending from the lower surface of said rocker member adjacent the outer edge thereof, and an inclined thrust plate secured to said rocker member and said object and extending over the line of attachment therebetween, said thrust plate and said retaining flange cooperating with the lower surface of said rocker member to form a wedging channel receiving and retaining a portion of said lifting sling in fixed position with respect to said object when lifting force is applied thereto through said sling.

3. In sling guiding means for use in erecting a cumbersome object with a derrick or the like having a lifting sling including at least one cable bight, a pair of lugs rigidly secured to opposite sides of said object in substantial alignment, said lugs having means engageable with spaced portions of a sling extending at least partially around said object below said lugs to prevent passage of said sling past said lugs and comprising a member having an arcuate sling engaging surface substantially perpendicular to said object, a retaining flange adjacent the outer edge of said arcuate sling engaging surface, and a thrust plate spaced inwardly of said retaining flange and cooperating therewith wedgingly to engage a sling portion.

4. In combination with a cumbersome object to be lifted and erected by a derrick or the like with a lifting sling, sling-guiding means comprising a pair of spaced lugs projecting outwardly from opposite sides of said object, each of said lugs including a shelf-like portion welded to said object and forming a downwardly facing abutment for an underlying sling extending around the object, to prevent upward slippage of the sling, said portion of each lug having an upturned end for training a suspension reach of the sling, and a bracing structure for said portion of the lug at the upper side thereof and welded to said lug portion and to said object.
5. In combination with a cumbersome object to be lifted and erected by a derrick or the like with a lifting sling, sling-guiding means comprising a pair of lugs projecting outwardly from said object at opposite sides and rigidly secured to said object, each of said lugs including a member with a substantially flat central portion adapted to be disposed substantially horizontal in the final position of said object and an upwardly directed arcuate portion extending from one end of said substantially flat portion and integral therewith, and a retaining flange depending from the lower surface of said member adjacent the outer edge thereof, said retaining flanges being adapted to engage a portion of a sling passing around said object below said lugs to retain said sling in position during erection of said object.
